UNITED STATES PATENT OFFICE.

FLORUS F. LAWRENCE, OF COLUMBUS, OHIO.

SURGEON'S OPERATING-TABLE.

No. 832,680.

Specification of Letters Patent.

Patented Oct. 9, 1906.

Application filed October 9, 1902. Serial No. 126,389.

To all whom it may concern:

Be it known that I, FLORUS F. LAWRENCE, a citizen of the United States, residing at Columbus, in the county of Franklin and State of Ohio, have invented a certain new and useful Improvement in Surgeons' Operating-Tables, of which the following is a specification.

My invention relates to the improvement of surgeons' operating-tables; and the objects of my invention are to provide an improved table of this class of superior construction and arrangement of parts, to provide improved means for permitting a rotary movement of the table-top and for locking the same against rotation, to provide in conjunction therewith improved means for adjustably supporting the table-top upon the supporting-frame, and to produce other improvements the details of which will be more fully pointed out hereinafter. These objects I accomplish in the manner illustrated in the accompanying drawings, in which—

Figure 1 is a side elevation of my improved table, showing a portion of one end broken away. Fig. 2 is an end view of the same. Fig. 3 is an under side view of a portion of the table with the leg-frame removed, and Fig. 4 is a detail view showing the inner face 30 of one of the keepers which I employ in the manner hereinafter described in connection with two of the legs of the table.

Similar numerals refer to similar parts throughout the several views.

In carrying out my invention I employ a supporting or leg frame comprising two oppositely-arranged and substantially yoke-like frame-bars 1, the upper portion of each of which is provided with a projecting ear or lug 2, with which lugs are pivotally connected the parallel side bars 3^a of a frame 3, which consists of said side bars united by transverse bars 4 and 5. The side bars 3^a are preferably in the nature of angle-bars and at what I will term their "forward" ends are connected by a transverse rod 6. They are likewise connected near the centers of their lengths with a transverse rod 7, the ends of which bear pivotally in the lugs 2. Rising from the frame 3 are short supporting posts or pins 7^a, with the upper ends of which is connected the under side of a lower turn-table ring 8, upon which is rotatably mounted an upper ring 9, this upper ring being connected through the medium of vertical pins or posts 10 with the under side of an oblong

table-top 11. While these rings 9 and 8 are, as shown in the drawings, supported one upon the other, they may be in the nature of channel-bars in cross-section, thus permitting the upper ring to run within the lower ring. In the construction shown I have provided ring-connecting clips or yokes 12, the lower sides of which are secured to the under side of the lower ring 8 and the upper sides of which loosely embrace the upper and inner sides of the upper ring, these clips serving to retain said rings in their relative positions. In the periphery of the lower ring I provide at intervals recesses or notches 13. Depending from the under side of the table-top at a point above the upper ring is a suitable pin 14, with which is pivotally connected the inner end of a horizontally-disposed lever 15, this lever terminating in a downturned handle portion 15^a and having its body portion curved outwardly, as shown more clearly in Fig. 3 of the drawings. Formed with the inner side of the lever-body at the center of its curved portion and extending downward from said lever is a lug or dog 16, which has projecting inwardly therefrom a tooth 17, said tooth being adapted to enter the desired one of the notches 13 of said lower ring 8. The lever is normally pressed inward, so as to facilitate the engagement of the tooth 17 with the notches of the ring 8 by means of a coiled spring 18, one end of which is connected with said lever and the remaining end of which is connected with a pin on the upper side of the upper ring 9. I also provide the upper side of said upper ring 9 with an outwardly-extending bar 19, which forms a bearing for the outer portion of the lever 15. As shown in Fig. 3 of the drawings, the lower ring 8 is connected with the frame cross-bar 5 and an upper ring cross-bar 20 through the medium of a bar 21, the connection with the bar 20 being pivotal.

At the forward end portion of each of the frame-bars 3^a is pivoted the upper or outer end of a curved bar 22, the rear side of which is toothed, as indicated at 23. The curved rack-bars thus formed and supported extend downward and rearward between the inner sides of the forward leg portions 1^a of the leg-frame 1 and keeper-brackets 24, which project from the inner sides of said leg portions. The upper arm of each of said brackets is, as shown more clearly in Fig. 4 of the drawings, formed with a downwardly-projecting tooth portion 25, and through the

lower portions of the keepers 24 passes loosely a shaft 26, said shaft being journaled in the leg portions 1^a and carrying within each of the keepers a cam-body 27, said cams 5 being adapted when properly turned to press the rack-bars 22 upward and cause an engagement of notches or teeth thereof with the teeth 25 of the keepers.

From the construction described it will be 10 observed that the table-top may be rotated upon its support by first pressing the lever 15 outward until the tooth 17 of its dog is out of engagement with a recess of the lower ring 8, and in the operation of rotating said table it 15 is obvious that the upper ring 9 will turn upon the lower ring 8. In order to tip the table-top until the same stands at a desired angle from a horizontal position, it will be understood that the rod or shaft 26 is 20 turned until the longer portions of the cams 27 are dropped downward until the teeth of the bars 23 are out of engagement with the teeth 25 of the keepers 24, after which the table may be tipped to the desired position 25 and locked in this tipped position by again turning the longer portions of the cams upward. It is obvious that when the table-top is turned at right angles with the position shown in the drawings the above-described 30 tipping operation will result in said table-top being tipped laterally and that the tipping of the same sidewise or endwise will depend upon the position of said table-top with relation to its support at the time of the tipping 35 operation.

Having now fully described my invention, what I claim, and desire to secure by Letters Patent, is—

1. A table of the class described, comprising 40 in its entirety, a supporting-frame, a tilting frame pivotally mounted on said supporting-frame, means for locking said tilting frame at any angle at which it may be set with relation to said supporting-frame, a sectional turn-table, comprising superimposed annuli coextensive throughout, the lowermost annulus being rigidly secured to said tilting frame and being provided with an inwardly-projecting bar following the radial

line thereof, the uppermost annulus being 50 provided with a transverse bar following the diametrical line thereof and pivoted at a central point to said inwardly-projecting bar, a table rigidly mounted on said uppermost annulus, said lowermost annulus being formed at 55 regular intervals with a series of recesses in its periphery and a lever pivoted at its end to the underneath side of said table, said lever being provided with a depending tooth for engagement with any one of said recesses and being 60 spring-held into locking engagement with said lowermost annulus.

2. A table of the class described, comprising in its entirety a supporting-frame, a tilting frame pivotally mounted on said supporting-frame, means for locking said tilting frame at any angle at which it may be set with relation to said supporting-frame, a sectional turn-table comprising superimposed annuli coextensive throughout and having 70 their peripheries in annular alinement, the lowermost annulus being rigidly secured to said tilting frame and being provided with an inwardly-projecting bar following the radial line thereof, the uppermost annulus being 75 provided with a transverse bar following the diametrical line thereof and pivoted at a central point to said inwardly-projecting bar, said lowermost annulus being provided with a plurality of upwardly-extending inturned 80 flanges loosely engaging said uppermost annulus and serving as retaining means therefor in its superimposed relation, a table rigidly mounted on said uppermost annulus, said lowermost annulus being formed at 85 regular intervals with a series of recesses in its periphery, and a lever pivoted at its end to the underneath side of the table, said lever being provided with a depending tooth for engagement with any one of said recesses and being 90 spring-held against said lowermost annulus, whereby said tooth will enter into locking engagement with any one of the peripheral recesses of said lowermost annulus.

FLORUS F. LAWRENCE.
